UNITED STATES PATENT OFFICE.

STEPHEN BALKWILL, OF CLEVELAND, OHIO, AND JAMES B. STRONG, OF HILLBURN, NEW YORK; SAID STRONG ASSIGNOR OF HIS RIGHT TO THE BALKWILL MANGANESE CROSSING COMPANY, OF CLEVELAND, OHIO, A CORPORATION OF OHIO.

RAILROAD-CROSSING.

1,315,004.

Specification of Letters Patent. Patented Sept. 2, 1919.

Application filed May 13, 1918. Serial No. 234,036.

To all whom it may concern:

Be it known that we, STEPHEN BALKWILL and JAMES B. STRONG, citizens of the United States, and residents, respectively, of Cleveland, in the county of Cuyahoga and State of Ohio, and Hillburn, in the county of Rockland and State of New York, have invented a certain new and useful Improvement in Railroad-Crossings, of which the following is a full, clear, and exact description.

This invention relates to a cast crossing suitable for use in railroad track work or for analogous uses.

15 The object of the invention is to provide a crossing in which the crossing is cast in separate parts, which, when assembled comprise a complete crossing, and the manner of engagement of the several parts is such as to permit a limited amount of flexibility between the parts of the crossing, particularly at those portions which in service most frequently fracture where solid castings are used.

25 A further object of the invention is to provide a construction whereby those portions of the crossing receiving the greatest amount of wear may be renewed, and in carrying this into effect each of the corner castings of the crossing embody all of the parts subject to excessive wear; thereby relieving the heavier and more expensive castings which are intermediate of the crossing members. These renewable corner castings 30 may be replaced when they become badly worn or damaged from any cause, without renewal of the heavier intermediate castings, thereby securing full life for the intermediate castings and providing a crossing 35 which is low in its cost of upkeep.

A further object is to provide a construction in which the center plate, upon which the flangeways intersect, is secured to the corner casting thereby avoiding difficulties 45 with respect to holding the center-plate in place where the center-plate is not a part of the casting. This construction enables the full wearing life of the center-plate to be obtained.

50 Generally speaking, the invention may be said to comprise the elements and combinations thereof set forth in the accompanying claims.

Reference should be had to the accompanying drawings forming a part of this specification, in which Figure 1 is a top plan view of a portion of a crossing embodying our invention; Fig. 2 is a top plan view of a portion of a crossing embodying our invention with certain modifications; Fig. 3 is a top plan view of an element of the crossing; Fig. 4 is a top plan view of an element of the crossing; Fig. 5 is a top plan view of a knee bar by which portions of the crossing are secured together; Fig. 6 is a top plan view of an element of a modified form of crossing; Fig. 7 is a top plan view of an element of a modified form of crossing; Fig. 8 shows rail sections which coöperate with the parts shown in Figs. 6 and 7; Fig. 9 is a top plan view of a knee bar for securing parts of the crossing together; Fig. 10 is a section upon the lines A—A of Figs. 1 and 2; Fig. 11 is a section upon the line F—F of Fig. 2; Fig. 12 is a section upon the line E—E of Fig. 1; and Fig. 13 is a section upon the line B—B of Fig. 2.

Crossings which are made up as solid castings are very prone to break along a line at the bottom of the wheel flangeways adjacent to the portion where the wheel flangeways of intersecting tracks cross. A fracture of the crossing in this manner results in the necessity for replacing the entire crossing, and such fractures frequently take place even though the wearing qualities of the crossing are not nearly exhausted.

The crossing herein proposed is made up of a number of coöoperating parts which form intersecting wheel flangeways in the top surface of the crossing, and the parts coöperate in such a manner that there is a limited amount of flexibility between the parts of the crossing, particularly at those portions of the crossing adjacent the point where the wheel flangeways intersect each other, which flexibility permits a slight relative movement between the parts and by so much takes care of the strains and stresses which in solid cast crossings are the causes of fracture of the crossing.

In Fig. 1 a portion of a crossing is shown, a complete crossing consisting of four parts, such as illustrated at 1, and four parts such as indicated at 2. It will be understood that the remaining portion of the crossing is

made up in the same manner as that indicated at Fig. 1.

The member 1 is U-shaped, and comprises the central portion 1^a with the arms 1^b, 1^c.
 5 The portion 1^a has formed therein a wheel flange groove 1^d and the portion of the casting 1^e which lies beyond the groove 1^d forms a guard for the flange of the wheel, while the portion 1^a adjacent the groove is the 70
 10 tread portion over which the periphery of a car wheel may run.

The arms 1^c and 1^b each form guard portions that coöperate with the adjacent corner members 2 of the crossing. A detached 75
 15 view showing the construction of member 1 is shown in Fig. 3.

A corner member such as indicated at 2 is shown in detached position in Fig. 4. Each corner member comprises two arm portions 2^a and 2^b. The arms portions 2^a, 2^b, are notched out adjacent their ends as indicated at 2^c for the purpose of receiving the 80
 20 end of a rail of a track with which the crossing coöperates. Adjacent the grooves 2^c and near the central portion of a corner member there are tread portions 2^d which coöperate with wheel flange grooves 2^e which are formed in the member 2 adjacent the 85
 25 tread portions.

30 Formed integral with the member 2 as an extension is the portion indicated at 2^f, in which portion there are formed intersecting flangeways 2^g which constitute continuations of the partial flangeways 2^e formed in the 90
 35 member 2. At the sides of the portion 2^f there are extensions 2^h, these extensions being indicated in Fig. 10, and these extensions 2^h coöperate with complementary grooves 1^f formed in a portion of the members 1 which are adjacent to a corner 2.

Each of the members 2 adjacent the partially formed wheel flange grooves 2^e thereof are provided with extensions 2ⁱ which coöperate with groove portions formed in the 95
 45 adjacent members 1, such as indicated at 1^g in Fig. 3.

When the crossing is assembled, and the projections 2^h and 2ⁱ occupy the respective recesses 1^f and 1^g, formed in the members 1 which are adjacent to a member 2, the various portions of the crossing are secured together by transversely extending bolts, such as indicated by the dotted lines 3 in Fig. 1.

Upon what we may term the inside of the 55 crossing, that is to say, within the hollow square formed by the assembled parts of the crossing, the knee bars or straps 4 are placed at the corners, and are fastened by suitable bolts to the members of the crossing with 60 which each knee bar coöperates, thus binding the portions of the crossing securely together.

It will be seen that each wheel flange groove as it approaches the crossing of the 65 flangeways, is in part formed in a member 2

and in the arm of a member 1, and at this portion of the wheel flangeway there is such a connection as permits a limited amount of relative movement between the parts of the crossing so that those stresses and strains 70 which are set up in the crossing as a wheel passes over the crossing, are taken up by the relative movement of the parts without damage to the parts of the crossing.

It is at just such portions of a solid crossing that fractures very largely occur, and therefore it will be seen that we provide a fracture at these portions in advance and so secure them together that the stresses and strains are taken up by the limited amount of relative movement which is permitted between the parts.

The projecting portion 2^f of the member 2 also has a certain amount of flexibility in their connection with the members 1 which are adjacent thereto in a crossing.

While we have shown and described projections 2^j and 2^k as formed upon the member 2 and coöoperating recesses 1^f and 1^g formed upon the member 1, it will be readily understood that it is within the scope of our invention to transpose these projections and recesses, thereby having projections similar to the projections 2^h and 2ⁱ formed upon the member 1, and recesses similar to the recesses 1^f, 1^g, formed in the member 2.

If it be desired, instead of forming the member 1 so as to have the wheel flange guard 1^e cast integral with the member 1, we may provide a separate bolted on wheel flange guard member; this may be readily done as is illustrated in Figs. 2, 6, 7, 8 and 9.

In this form of crossing there are four members, such as indicated at 5, and four corner members such as indicated at 6, which members coöperate, when forming a crossing in the same manner as indicated in Fig. 2.

The construction of the member 5 is similar in all respects to the construction of the member 1, as before described, except the extension 5^a is lower than the top or tread portion 5^b of the member 5, and requires a rail member such as indicated at 7, to be secured to the member 5 against the extension 5^a, which construction provides a wheel flangeway between the member 5 and the guard rail 7. It will be understood that the guard rail is secured to the member 5. There are four such guard rails for a crossing which meet and are mitered at their corners, and are secured to the parts of the crossing by bolts, or other suitable means, such as will readily be understood.

The member 6 is similar in all respects to the part 2, except that in the extension 6^a, 125 the front or forward portion thereof as indicated at 6^b is formed to receive the end portion of the guard rails 7.

When the various portions of the crossing are secured together the knee bar mem- 130

bers 8 are secured at the corners where the rails 7 meet, and so form tying members between the various portions of the crossing.

Having described our invention, we

5 claim:—

1. In a railroad crossing, the combination of a corner member having arms with wheel tread portions thereon, and having a plate like extension having sides which extend at 10 an angle to the arms, said extension being adjacent the intersection of the arms and having complete wheel flangeways formed therein, and coöoperating crossing members formed with wheel tread portions which 15 aline with the wheel tread portions of the corner member.
2. In a railroad crossing, the combination of a corner member having arms with wheel tread portions thereon formed with partial 20 wheel flangeways therein and having a plate like member with complete wheel flangeways formed therein, said member extending from the corner member adjacent the intersection of the arms, and coöperating 25 crossing members having arms which coöperate with the arms of the corner member to complete the partially formed flangeways of the corner members, said coöperating members having portions which receive and fit 30 with the said plate like member.
3. In a railroad crossing, the combination of corner members and intermediate members, said intermediate members having wheel flangeways formed in the top thereof, 35 said intermediate members also having arms, said corner members having arms with partially formed wheel flangeways therein, which arms coöperate with the arms of adjacent intermediate members to form complete 40 wheel flangeways, said corner members each having an extending portion which has wheel flangeways formed in the top thereof, each of said extending portions engaging with the intermediate members adjacent thereto, whereby the wheel flangeways of the 45 projecting portion aline with the wheel flange grooves formed in and by the other members of the crossing when the several members of the crossing are assembled.
- 50 4. In a railway crossing, the combination of members each having a part with a tread portion and an arm element formed as a guard, and other members forming a corner having elements each of which form a tread portion, said corner members also having an 55 extension formed with wheel flangeways in the top thereof, each arm element before

mentioned engaging with an element of a corner member forming a tread portion above the base of said member thereby to 60 form a wheel flangeway, one of the engaging elements being formed with a depression above the base thereof, and the other being formed with a projection which coöperates with the said depression.

5. In a railway crossing, the combination of members each having a rim with a tread portion and an arm element formed as a guard, and other members forming corners having elements each of which forms a tread portion, said corner members each being provided with a projection having wheel flangeways formed in the top thereof, each arm element before mentioned engaging with an element forming a tread portion above the 70 base of said member thereby to form wheel flangeways, one of the engaging elements being formed with a depression above the base thereof, and the other being formed with a projection which coöperates with the 75 said depression, each of said members and the projecting portion of each corner member being formed with engaging projections and depressions whereby the projecting portion of the corner member when in position 80 is supported by the crossing members.

6. A railway crossing having approach portions, each approach portion being formed in two parts, said parts coöoperating to form a wheel flangeway, the said parts 90 engaging along the surface of contact at which the parts are secured together, one of the parts being formed with a projection and the other with a depression above the base thereof, the projection engaging the 95 depression whereby the engaging member is supported in part by the engaged member and in part independently supported thereby permitting a limited amount of flexibility in the connection, a projection formed integrally with one of the parts, forming an approach, which projection is provided with wheel flange grooves in the top thereof, the projecting portion engaging with and supported in part by the other of the approach 100 parts before mentioned.

In testimony whereof, we hereunto affix our signatures.

STEPHEN BALKWILL,
JAMES B. STRONG.
